CLAIM

The ornamental design for a portable glass holder or similar article, as shown.

DESCRIPTION

FIG. 1 is a perspective view of a portable glass holder or similar article showing our new design;
FIG. 2 is a rear elevational view thereof;
FIG. 3 is a front elevational view thereof;
FIG. 4 is a left side elevational view, the right side being a mirror image thereof;
FIG. 5 is a top plan view thereof; and,
FIG. 6 is a bottom plan view thereof.
